HANDWHEEL

Frederick J. Stolpe, Chicago, Ill., assignor to Poor & Company, Chicago, Ill., a corporation of Delaware

Application August 18, 1937, Serial No. 159,753

1 Claim. (Cl. 74—552)

This invention relates to handwheels, particularly for use on hand brake mechanisms of railway freight cars, although readily capable of various other uses, and has for one of its objects to provide a handwheel which is strong and durable and yet is of very materially reduced weight as compared with known handwheels, whereby tendency of the same to become loose on the shaft to which it is applied, and whereby wear 10 on the shaft bearings, is correspondingly reduced.

Another object of the invention is to provide a handwheel including a hub, preferably of forged steel, which is manufactured as an element separate from the wheel proper and which has the 15 wheel proper welded, riveted or otherwise suitably fastened thereto, thereby to provide for obtaining far greater accuracy in the hub construction than has been possible heretofore under the usual practice of casting the hub as an integral 20 part of the wheel.

Another object of the invention is to provide a handwheel having a novel rim and web construction combining strength with light weight and affording comfortable hand engaging portions 25 and finger accommodating openings designed to avoid cramping of the fingers.

Another object of the invention is to provide a handwheel embodying a novel design to prevent an operator from passing his hand through the 30 wheel with possible resultant injury, and to discourage the use of a "club" for turning the wheel by rendering the use of a "club" substantially impossible.

Another object of the invention is to provide 35 for mounting the present handwheel on the operating shaft of a well known type of brake gear very closely adjacent to the outer bearing of the shaft, thus to further relieve such bearing of strain and wear.

With the foregoing and other objects in view, which will become more fully apparent as the 40 nature of the invention is better understood, the same consists in the novel combination and arrangement of features as will be hereinafter more fully described, illustrated in the accompanying drawing and defined in the appended claim.

In the accompanying drawing, wherein like 45 characters of reference denote corresponding parts in the different views:

Figure 1 is a front elevation of a handwheel 50 constructed in accordance with the invention.

Figure 2 is a cross section on the line 2—2 of Figure 1.

Figures 3 and 4 are detail sections on the lines 55 3—3 and 4—4, respectively, of Figure 1; and

Figure 5 is a sectional view illustrating an alternative embodiment of the invention.

Referring to the drawing in detail, first with particular reference to the form of the invention illustrated in Figures 1 to 4, it will be observed that the present handwheel comprises, as usual, a wheel proper, designated generally as A, and a hub designated generally as B, but that, as distinguished from the general prior practice of casting the wheel proper and the hub in one-piece, the present wheel proper and hub are separately formed parts rigidly united with each other, either by welding as shown, or in any other suitable or desired manner.

According to the general prior practice of casting the hub and the wheel proper of a handwheel in one piece it is difficult and practically impossible, due to warpage and other causes, to obtain accurate hub measurements and uniformity as between a series of successively produced wheels. 15 Therefore, the usual one-piece cast handwheel does not, as a rule, accurately fit the shaft to which it is applied, which is one reason why it tends soon to become loose on its shaft. By separately forming the hub and the wheel proper 20 the hub may practicably be forged to exact measurements. It thus possesses greater strength 25 than the usual cast hub and will accurately fit its shaft, so that any tendency of the same to become loose because of an inaccurate fit is eliminated. 30

The present wheel proper A instead of being cast in accordance with prior general practice, is pressed from sheet steel in a manner to impart great stiffness thereto. It may, therefore, be 35 formed from relatively thin sheet steel with a material saving in metal and especially with a considerable saving in weight, without sacrifice in strength, as compared with the usual cast handwheel. This is quite important, particularly 40 regarding the saving in weight when the wheel is employed under conditions where it is subjected to being laterally shifted, as, for example, upon the brake mechanism of a railway car, for the constant swaying and surging of the car 45 in transit and during switching operations, combined with the inertia of the handwheel, causes wear on the bearings of the shaft on which the wheel is mounted directly proportional to the weight of the wheel. Accordingly, because of the 50 reduced weight of the present handwheel, there is a corresponding reduction in wear on the bearings of the shaft on which the wheel is mounted, under conditions where the wheel is subjected to being laterally shifted as aforesaid. Moreover,

by pressing the present wheel proper from sheet steel the same may readily be straightened if for any reason it should become bent; whereas, the usual cast wheel ordinarily would become broken or fractured and, in any event, rendered unfit for further service if subjected to a force required to bend the present wheel. Furthermore, loosening of a handwheel on its shaft is due largely to the same causes which produce wear on the shaft bearings. Therefore, because of the reduced weight of the present wheel its tendency to become loose on its shaft is correspondingly reduced.

The wheel proper, A, is of dished form cross-sectionally and comprises a rim 10, a central disk-like portion 11, a ring-like portion 12 between said rim 10 and said central disk-like portion 11, spokes 13 connecting said central disk-like portion 11 with said ring-like portion 12, and spokes 14 connecting said rim 10 with said ring-like portion 12.

The rim 10, the spokes 14 and the outer edge of the ring-like portion 12 are formed by punching finger accommodating openings 15 in the wheel proper, and, during the operation of pressing the wheel proper to shape, the metal surrounding these openings, i. e., the metal comprising the inner edge of the rim 10, the edges of the spokes 14 and the outer edge of the ring-like portion 12 is flanged outwardly as indicated at 16, thereby imparting great strength to the inner edge portion of said rim 10, to the spokes 14 and to the outer part of the ring-like portion 12. The outer edge portion of the rim 10 also is flanged outwardly as indicated at 17 and this flanging, in conjunction with the outward flanging of the inner portion of said rim, imparts to the latter substantially semi-circular cross-sectional shape, so that the same is quite stiff and strong and is comfortable to grasp. Moreover, said rim 10 is provided at spaced intervals with series of indentations 18 which greatly facilitate obtaining a firm grip thereon.

The outer edge of the central disk-like portion 11, the spokes 13 and the inner edge of the ring-like portion 12 are formed by punching holes 19 in the wheel proper, and, during the operation of pressing the wheel proper to shape, the metal surrounding these openings also is flanged outwardly as indicated at 20, thereby imparting strength to the outer edge portion of the disk-like portion 11, to the spokes 13 and to the inner edge portion of the ring-like portion 12. In addition, the spokes 13, which preferably are straight and radially disposed as shown, may be and preferably are stiffened and reinforced by ribs 21, extending longitudinally thereof and pressed outwardly therefrom as shown, these ribs preferably extending into the ring-like portion 12 and into the disk-like portion 11.

While the spokes 14 may be of any suitable type, they preferably are of the spiral type and merge gradually into the rim 10 to insure against cramping of the fingers when rotating the wheel to tighten the brake. Moreover, the inner end portions of the spokes 13 preferably are alined with the spokes 14, respectively, to further increase the strength of the wheel. In any event, due to interposing the ring-like portion 12 between the

rim 10 and the central disk-like portion of the wheel, it is practically impossible to employ a "club" for rotating the wheel. Moreover, the said ring-like portion 12 serves additionally as a guard preventing insertion of the hand through the 5 wheel.

In the central disk-like portion 11 of the wheel proper, centrally thereof, is formed an opening 22 of a size and shape to neatly accommodate the hub B, thereby to provide for accurately centering said hub with respect to said wheel proper. The hub is provided intermediate its ends with an external, continuous lateral flange 23 against which the central disk-like portion 11 of the wheel proper seats when the hub and the wheel 15 proper are assembled by inserting the hub into the opening 22, and the hub and the wheel proper are rigidly united either by welding, riveting or otherwise suitably fastening the flange 23 and the central disk-like portion 11 together. 20 Through the hub is formed a preferably tapered opening of suitable cross-sectional shape to accommodate the correspondingly shaped end of the shaft to which the wheel is to be applied.

In some cases it may be desirable to locate 25 the present handwheel very close to the outer bearing of the shaft to which the wheel is applied, as, for example, in the use of the wheel on hand brakes of the general type disclosed in Klasing Patent No. 1,927,237, as in this way strain 30 and wear on the bearing may be materially reduced. This may be accomplished according to the present invention and as illustrated in Fig. 5 of the drawing by forming on or suitably fastening to the outer end of the operating shaft 24 of 35 the brake a flange 25 which, in the operative position of said shaft, is disposed closely adjacent to the outer bearing 26 of said shaft, and by riveting, welding or otherwise fastening the central, disk-like portion 11 of the wheel A directly to 40 said flange.

Without further description it is thought that the features and advantages of the invention will be readily apparent to those skilled in the art, and it will, of course, be understood that changes 45 in the form, proportion and minor details of construction may be resorted to, without departing from the spirit of the invention and scope of the appended claim.

I claim:

A handwheel comprising a wheel proper of 50 pressed sheet metal including a central disk-like portion, a rim, a ring-like portion between said central disk-like portion and said rim, straight radial spokes connecting said disk-like and ring-like portions, other spokes of substantially spiral 55 form connecting said rim and said ring-like portion, the marginal parts of said rim and spokes and of said ring-like and disk-like portions being laterally flanged, the inner ends of said spiral 60 spokes being alined with said straight radial spokes, and reinforcing ribs extending longitudinally along said straight radial spokes into said central disk-like portion and into said ring-like portion, said reinforcing ribs being pressed from 65 said spokes and from said disk-like and ring-like portions in the same direction as said marginal flanges.

FREDERICK J. STOLPE.
